Gardiner & Sly, Esq.

United States Patent Office.

JOHN HOLTZ, OF BALTIMORE, MARYLAND.

Letters Patent No. 88,168, dated March 23, 1869.

IMPROVEMENT IN AUTOMATIC BOILER-FEEDERS.

The Schedule referred to in these Letters Patent and making part of the same.

To all whom it may concern:

Be it known that I, JOHN HOLTZ, of Baltimore, State of Maryland, have invented a new and useful Device for Economizing the Steam and Water of Boilers of Steam-Engines; and I do hereby declare that the following is a full and exact description thereof, reference being had to the accompanying drawings, and to the letters of reference marked thereon.

In the drawings—

Figure I is a side sectional view, and

Figure II, an end sectional view of my device.

The nature of my invention consists in providing the escape-pipes of steam-boilers with a device by which, while the escape of steam is regulated, a large portion of it is returned condensed to the boiler, to become steam again.

In construction, I form my invention as follows:

In or on the escape-pipe A, of the boiler, is screwed the pipe B, forming a prolongation of the pipe A, and permitting the steam to flow unobstructed to its head b, (a plug tightly screwed in,) upon the pipe B; and at or near its junction with the escape-pipe A, is screwed a cylinder-head, a, to which is attached, by a coupling, e, a tube, C, of the same size, the tube C being as much larger than the inner tube B as is required, and extending its full length.

To the end of this tube is attached, by means of couplings d and e, the pipe f, through which the partially-condensed steam finally escapes to the air.

Through the tube B, at a proper distance from its end, b, is an aperture, D, much smaller in diameter than the bore of tube B, and which may be bevelled, if it is necessary, to form a tighter valve-seat.

Fitting into this is the valve-head g, of the screw-valve G, which is let through the outer pipe C, and which forms a shoulder for it, so that it may be screwed to completely close the aperture D, or unscrewed so as to offer no obstruction to the flow of the steam.

Upon the screw G, outside of the tube C, I place a

nut, h, to act as a gauge to regulate the depth to which it is desirable to screw the valve, and also to act as an additional shoulder to steady the valve when screwed into its seat.

Nearly opposite the aperture D, I place a minute opening in the pipe B, so that when the hole D is entirely closed, there will be escape of steam enough to give warning if the steam from a safety-valve is blowing off.

The operation of this device is as follows:

The steam coming from the boiler, passes through the pipe B, until, coming in contact with the head of the pipe, at t, it is forced through the aperture D, which, being smaller than the interior of the pipe B, causes the escaping column of steam to receive an increased degree of momentum proportionate to the difference of sizes in the respective diameters of tube B and opening D. This column of steam, with its great momentum, coming in contact with the valve-head, is, a large part of it, condensed at once, and percutted back to the boiler as water, thus saving a large amount of water ready at once to be converted into steam again, and tending to prevent the steam already in the boiler from being superheated, by insuring a supply of water to the boiler at different parts of it.

I do not confine myself to claiming the exact arrangement of the parts as shown, as they may be differently modified without affecting the illustration of the principle.

Now, having described my invention,

What I claim as new, and desire to secure by Letters Patent, is—

A device for percutting water of condensed steam to the boiler, substantially as shown and described.

JOHN HOLTZ.
